UNITED STATES PATENT OFFICE.

MIKE KOSKE, OF MCLOUD, CALIFORNIA.

COMBINATION TOOL.

Application filed November 30, 1925. Serial No. 72,273.

My invention relates to improvements in combination tools.

An important object of my invention is to provide a tool embodying a number of instrumentalities, such as a wrench, a chisel, and a punch, having a common handle, the instrumentalities being arranged in such relation on the handle that the latter may be used for receiving the blows of a hammer in using either the punch or the chisel.

Another object of my invention is the provision of a tool which fulfills the requirements above indicated and in which the handle serves as a housing for receiving a foldable wrench element.

Other objects such as low cost of manufacture and simplicity in construction are also comprehended by my invention, all of which will presently appear when the following description and claims are read with reference to the drawing accompanying and forming a part of this specification.

In said drawing:

Fig. 1 is a side elevational view of a tool constructed in accordance with my invention, a portion of the handle being broken away and shown in section; and

Fig. 2 is an edge view looking toward the left of Fig. 1.

Referring to the drawing by numerals, 1 designates the handle portion of my novel tool, 2 the wrench element, 3 the chisel, and 4 the punch. The handle portion 1 is preferably in the form of an elongated body of rectangular shape in cross-section, and is provided intermediate its ends with a concave edge 5 for securing a better hand grip on the tool. A chamber or recess 6 is formed in the handle 1 and opened at the opposite edge of the handle portion from that at which the concaved edge 5 is formed. Within the chamber 6 a wrench head 7 is pivoted at one end as at 8 so that it may be swung out of the chamber to project from the handle portion 1. The pivot 8 of the wrench element 2 is arranged in the chamber 6 so that in its projected position a portion of said element 2 abuts one end wall of the chamber whereby, when the wrench element is in use, the tool may be turned in an operative direction without relative movement occurring between the handle portion 1 and wrench element 2. When not in use the wrench element may be swung on its pivot 8 into the chamber 6. The pivoted end of

the wrench element is squared so that, in this idle position, it may be engaged by a flat spring 9, suitably secured within the chamber 6, and yieldingly held against accidental projection from the handle portion 1. The chisel 3 and punch 4 and which are of usual tapering formation, project longitudinally from opposite ends of the handle portion 1 and are located adjacent opposite edges thereof with their longitudinal axes in parallel offset relation to the longitudinal center of the handle portion, whereby at either end of the handle portion a butt 10 is provided for driving the instrumentality at the opposite end. As will be observed, these butts form flat driving surfaces at each end of the handle portion, the faces of which lie in planes at a right angle to the longitudinal center of the handle portion. In short there is an instrumentality at either end of the handle portion 1 and likewise a butt 10 at each end, each butt 10 being in direct alignment with the instrumentality at the opposite end. The tool elements 3 and 4 at their base portions are of less area than that of the flat end faces of the hand grip for providing the driving butts at each end of the hand grip arranged in longitudinal alignment with the tool element carried by the opposite end of the hand grip.

The chisel 3 and punch 4 being tapered, present inclined inner faces extending at an obtuse angle from their adjacent butts or flat driving surfaces 10, which will each have a tendency to direct the blow of the hammer to the butt adjacent it, if the operator should, because of use of the tool in what might ordinarily be termed "inaccessible places" find it difficult to direct the blows of the hammer directly on the butt.

Obviously my invention is susceptible of modification without departing from the spirit thereof, and such modifications and changes as fall within the scope of the appended claims are intended to be comprehended by the present disclosure.

I claim:

1. A combination tool comprising an elongated body portion forming a hand grip provided with flat end faces, and tool elements projecting longitudinally of and from each end of the hand grip and disposed with their longitudinal axes in parallel offset relation, said tool elements at their base portions being of less area than the flat end faces of

the hand grip for providing driving butts at each end of the hand grip arranged in longitudinal alignment with the tool element carried by the opposite end of the hand grip.

5. 2. A combination tool comprising an elongated body portion forming a hand grip having flat driving surfaces provided at each end thereof and disposed in offset relation to opposite sides of the longitudinal center of

the hand grip, and tool elements extending 10 longitudinally from each end of the hand grip at opposite sides of the longitudinal center of the latter from said driving surfaces and each having an inclined inner face 15 extending at an obtuse angle from its adjacent driving surface.

MIKE KOSKE.
